UNITED STATES PATENT OFFICE.

JOHN P. ODGERS, OF PHILADELPHIA, PENNSYLVANIA, ASSIGNOR TO THE
A. M. COLLINS MANUFACTURING COMPANY, OF SAME PLACE.

DESIGN FOR A PHOTOGRAPHIC-CARD MOUNT.

SPECIFICATION forming part of Design No. 23,692, dated October 16, 1894.

Application filed July 25, 1894. Serial No. 518,589. Term of patent 7 years.

To all whom it may concern:

Be it known that I, JOHN P. ODGERS, a citizen of the United States, residing in Philadelphia, Pennsylvania, have invented a certain new and useful Design for Photograph-Card Mounts, of which the following is a specification.

My design is fully shown in the accompanying drawings, in which—

10 Figure 1, represents a face view of the card mount; and Fig. 2, an enlarged sectional view of the same.

15 The mount is of oblong rectangular outline and has a central oval medallion A bordered by an annular groove or depression a which is surrounded by a raised rib or head b. The face of the medallion A is plain, but the face of the mount outside of the rib b is grained or roughened and in each corner of the mount

is an ornament d representing a bunch of leafy twigs.

The essential feature of the design is the central medallion having a plain surface and contained within a mount of oblong rectangular outline having its surface, beyond the 25 medallion, grained or roughened and having the corner ornament d.

I claim—

20 The design for a photograph card mount, substantially as shown and described. 30

In testimony whereof I have signed my name to this specification in the presence of two subscribing witnesses.

JOHN P. ODGERS.

Witnesses:

WILLIAM A. BARR,
JOSEPH H. KLEIN.
